DISCONNECTOR SWITCH

Marvin Lee, Rye, and Irving Frederick Matthysse,
New York, N. Y., assignors to Burndy Engineering
Company, Inc., a corporation of New York

Application February 4, 1943, Serial No. 474,750

6 Claims. (Cl. 200—50)

This invention relates to a disconnecting switch whose contact blades may be permanently attached to the outgoing cable, removed at will from a switch base pivot, and transported with the cable.

In the building of ships a great deal of welding is now being done, to a large extent replacing riveting. The motor generator set supplying the current to the welding electrode is mounted on the ship and when the ship is moved from one working position to another, approaching the water's edge, the cable has to be disconnected at the safety switch and reconnected at the new position. It is inconvenient to have an electrician available at all times for this process of connecting and disconnecting the cable, and therefore it is an object of this invention to provide a device that permits the connection to be made by an unskilled workman quickly and safely, and without danger of reversing phases. Another object is to provide the disconnecter switch and attaching cable as a unitary assembly.

Plug and receptacle connectors which have been used for similar purposes have the disadvantage of poor contacts between the male and female conducting members. Experience has shown that the type of contacts employed in the plugs and receptacles frequently overheat under full load, particularly in the larger sizes. This condition is aggravated by wear after frequent use.

High pressure between contacts is necessary for a good electrical connection. However, the pressure between contacts of the ordinary plug and receptacle is limited due to the fact that the force required to insert the plug into the receptacle is the result of friction caused by the contact pressure. Therefore it is a further object of this invention to provide a disconnecter switch with switch blades of the leverage type having means for removing the blades from their fulcrums. Due to the leverage obtained in this manner, much greater contact pressure may be employed than is possible in the plug and receptacle connectors.

Another object is to provide a disconnecter switch with a switch blade ground connection which automatically "grounds" the ground conductor of the outgoing cable when the disconnecter switch is closed. This makes it impossible to connect the "phase" conductors without connecting the ground conductor.

We further may employ a safety switch to open the circuit before the disconnecter switch is

opened, to avoid arcing at the contacts. It is a further object of this invention to provide, in combination, a safety switch and a disconnecter switch with means for preventing the disconnecter switch from being opened unless the safety switch is open. This is accomplished by placing both within the same housing in such a manner that when the door of the housing is closed the disconnecter switch is locked in the closed position. The door is interlocked with the safety switch operating handle so that the door cannot be opened unless the safety switch is open, and therefore the disconnecter switch cannot be opened unless the safety switch is open.

Another object is to provide a disconnecter switch whose blades can engage only the proper switch clips. This prevents a careless workman from reversing the phases by incorrectly inserting the blades in the switch clips.

We accomplish these and other objects and obtain our new results as will be apparent from the device described in the following specification, particularly pointed out in the claims, and illustrated in the accompanying drawings, in which:

Fig. 1 is a plan view of our disconnecter switch and safety switch installed in a switch box (with cover partially removed).

Fig. 2 is a side elevation of the same with the side of the switch box partially removed.

Fig. 3 is a perspective view of the end of the disconnecter switch blade.

Fig. 4 is a side elevation of a portion of the disconnecter switch with a modified ground connection.

Fig. 5 is a sectional view of the disconnecter switch through the plane 5—5 of Fig. 4.

Referring to the drawings, Figs. 1 and 2, reference numeral 10 designates a switch box, provided with hinges 11 supporting the lid 12. The switch box contains a quick make and break safety switch 13 to which is connected the power source (not shown), and the disconnecter switch 14 which leads to the operating apparatus as will hereinafter be explained.

Extending through the side of the switch box is safety switch handle 15. The handle 15, box 10, safety switch 13, are of a type well-known in the art as a standard quick make and break interlocking cover switch. In this type of switch, the handle must be pulled to "open" position in order to open the switch box. Moreover, in this position, the switch cannot be closed when the lid of the box is open.

In Fig. 2, the contact blades 16 are shown

engaging the corresponding safety switch spring contact clips 47, mounted on the insulating base 18, supported on bracket 19, secured on the switch box floor 20. A jumper braid 21 connects the contact clips 47 to the conducting mounting strips 22 of the disconnector switch 14, constituting the switch terminals.

An insulating base block 23 supports the strips 22 to the metal box 20.

The disconnector switch 14 illustrated is of the four pole type for a three phase four wire cable 24 as shown. The fourth lead is the neutral lead 25, and is shown carried through both switches without grounding. The remaining leads 26, 27 and 28, together with the neutral lead 25 are enclosed within the insulated cable 24, and may be presumed to be connected to a welding apparatus or other device, not shown.

A portion of the switch, containing a handle, blades and associated connections which may be separated from the disconnector switch 14, and removed as a unitary assembly with the end of the cable, is designated as the jack 30. It comprises in detail a metal handle 31, divided in two halves and secured together about the insulation of the cable 24 by screws 32. Integrally extending from the handle 31 are four supporting legs 33, rectangularly positioned, provided with apertured lugs 34 for attachment to a pair of insulating blocks 35 by means of bolts 36. The insulating blocks 35 are locked together by four bolts 37. Insulated leads 25, 26, 27 and 28 are secured to the connections, i. e. pin type connectors 38 passing through grooves 39, in the blocks 35, and terminate in apertured and slotted clamping plates 40 into which slots are secured the switch knife blades 41, by cap screws 42. The insulating block bolts 37 pass through openings in the pin connectors 38 and prevent rotation of the knife blades 41 by keeping the faces of the blades parallel. The switch knife blades 41 are provided with U-shaped slots 43 at their free ends, as shown in Fig. 3, which engage the pins 44 supported on the hinge blocks 45. The hinge blocks are U-shaped metal sections with flat bases and the pins extend across the two legs of the block at their free ends to form a fulcrum for the U-shaped slots 43 of the knife blades 41. The hinge blocks 45 are supported on the mounting strips 22 to which the jumper braid 21 is connected, leading from the safety switch 13, and are bolted as at 46 to the insulating block 23.

Bolts 47 secure the spring switch clips 48 to the mounting strips 22 at a suitable point on the knife blades 41. The switch clips are U-shaped to facilitate receiving the knife blades, and are compressed thereon to insure contact by the wire springs 49 supported thereon. Screws 50 lock the insulating block 23 to the floor 20 of the switch box 10.

A slotted opening 51 in the end 52 of the switch box 10, permits the handle 31 of the jack 30 to be projected therethrough, and a cut-out extension 53 riveted as at 54 to the lid 12 of the box abuts the surface of the handle 31 in a semicircular engagement securing the jack in position when inserted into the disconnector switch.

The conductors are connected to their respective connectors 38 clamped to the knife blades 41 and the current from the jumper braids 21 enter the mounting strips 22 where it passes to the spring clips 48, where contact with the switch knife blades 41 is made.

In the event a workman desires to remove the jack 30, the handle 31 for the safety switch 13 must be thrown to open position. This allows the lid 12 of the switch box 10 to be opened. 5 and with the power disconnected, the end of the cable 24 with handle 31 attached to the insulating blocks 35 together with blades 41, constituting the jack 30, are removed as a unit from the spring clips 48 and the pins 44 of the hinge blocks 45 by pivoting the ends of the blades 41 about the pins 44, as shown in dotted lines in Fig. 2, and freeing the pins through the slots 43 of the blades.

While neutral lead 25 of the three phase system is shown provided with its own switch blade hinge block, jumper blade, etc., the switch may employ only three knife blades, and the ground lead may be connected as shown in Figs. 4 and 5. Here the ground cable 60 is secured to the U-bolt 61, which passes through apertures in the supporting frame 62 of the jack 63, and locked thereto by nuts 64. At the opposite side the frame 62 terminates in a knife blade 65 inserted within a spring clip 66 compressed by spring 67. A bolt 68 secures the clip 66 to clip platform 69, which in turn is mounted to the metal base 20 of the switch box 10 by means of the screws 70. Thus, in the downward stroke of the jack 63, to establish connection with the main current source, the ground connection may be established by this auxiliary means.

In Fig. 1, the distance between switch blades 41 from center to center, may be unequal. Thus, 15 incorrect insertion of the jack will be made impossible, for a 180° rotation about its longitudinal axis of the jack will not establish a correct matching of the fulcrums and switch clips. The jack under the unequal spacing of the engaging members can only be inserted when 20 in correct position.

In the foregoing devices, we have provided a disconnector type of switch which may be easily withdrawn and inserted in a highly efficient manner, by a relatively unskilled person. Our disconnector switch employs the spring type clips found in knife switches having blades with sufficient leverage from the fulcrum points to operate the high pressure spring clips. Associated 25 with the disconnector switch is a safety switch 30 with interlocking switch box cover to prevent accidental withdrawal of the disconnector jack under live loads. The disconnector switch may 35 additionally be provided with grounding means and unequally spaced blades to insure proper 40 alignment.

Our disconnector switch may be installed in 45 its own switch box or used in conjunction with other safety cut-out devices. The jack is combined with the cable itself to form a unitary 50 assembly to facilitate removal and use.

We have thus described our invention, but we 55 desire it understood that it is not confined to the particular forms or uses shown and described, the same being merely illustrative, and 60 that the invention may be carried out in other ways without departing from the spirit of our invention, and, therefore, we claim broadly the right to employ all equivalent instrumentalities 65 coming within the scope of the appended claims, 70 and by means of which, objects of our invention are attained, and new results accomplished, as it is obvious that the particular embodiments herein shown and described are only some of the many that can be employed to attain these objects and accomplish these results.

What we claim and desire to secure by Letters Patent is as follows:

1. A disconnector switch for connection to a device requiring electric current, said switch having a terminal and a connection to a cable leading to the device, comprising in combination a handle; a knife blade forming a rigid unitary structure therewith; means for connecting the cable to the knife blade; a hinge block for pivotally supporting the knife blade; a spring contact clip for engaging the knife blade; means for connecting the contact clip to the terminal; and means for readily detaching the knife blades from the hinge block and removing the handle, knife blade and cable connection as a unitary assembly from the disconnector switch.

2. A disconnector switch for connection to a device requiring electric current, said switch having a terminal and a connection to a cable leading to the device, comprising in combination an insulated handle; a knife blade forming a rigid unitary structure therewith; means for connecting the cable to the knife blade through said handle; a hinge block for pivotally supporting the knife blade; a spring contact clip for engaging the knife blade; means for connecting the contact clip to the terminal; and means for readily detaching the knife blades from the hinge block and removing the handle, knife blade and cable connection as a unitary assembly from the disconnector switch.

3. A disconnector switch for connection to a device requiring electric current, said switch having terminals and connections to a multi-conductor cable leading to the device, comprising an insulated handle; a plurality of knife blades forming a rigid unitary structure therewith; means for connecting each of the conductors to a knife blade; a hinge block for each of the knife blades for pivotally supporting the same; a spring contact clip for engaging each of the knife blades; means for connecting each of the contact clips to one of the terminals; said knife blades and corresponding contact clips being unequally spaced from each other so that engagement of the blades and contact clips can occur only when the knife blades are inserted into their proper contact clips.

4. A disconnector switch for connection to a device requiring electric current, said switch having a terminal and connections to a cable provided with a ground lead leading to the device,

comprising a handle; a knife blade forming a rigid unitary structure therewith; insulation positioned between said handle and knife blade; a hinge block for pivotally supporting the knife blade; a spring contact clip for engagement with the knife blade; means for connecting the contact clip to the terminal; a ground blade projecting from said handle in a direction normal to the knife blade; means for connecting the ground lead to said handle; a ground contact clip for engagement with said ground blade; terminal means for the ground contact clip; and means whereby the closing of the disconnector switch will simultaneously connect the ground blade to the ground contact clip.

5. A switch, comprising in combination a quick make and break safety switch leading to a source of supply; a disconnector switch in series therewith for connection to a device requiring electric current; and a housing therefor having a lid; means for automatically locking the lid of the housing when the safety switch is in closed position; said disconnector switch comprising a knife blade, handle forming a rigid unitary structure therewith, and means for connecting the knife blade to a cable, forming a rigid unitary assembly; a hinge block for pivotally and detachably supporting the knife blade thereto; said housing having an open slot for permitting said handle to be projected therethrough when the disconnector switch is in closed position, said lid when in closed position blocking the open end of the slot, to prevent removal of the handle.

6. A disconnector switch for connection to a device requiring electric current, said switch having a terminal, and a connection to a cable leading to the device, comprising a U-shaped hinge block provided with a pin extending from one leg of the U to the other; a spring contact clip; a conducting strip leading from the contact clip to the terminal of the disconnector switch, a readily removable jack consisting of a knife blade having a U-shaped end thereof for pivot engagement with the pin of the hinge block, a handle forming a rigid unitary structure therewith, and means for connecting the blade with the cable connection; said knife blade being in engagement with the spring clip when the Jack is inserted into the disconnector switch.

50
